UNITED STATES PATENT OFFICE.

WILLIAM A. BOCK AND RICHARD G. BOCK, OF CHICAGO, ILLINOIS.

RAIL-ANCHOR.

1,205,702.

specification of Letters Patent. Patented Nov. 21, 1916.

Application filed April 10, 1916. Serial No. 90,132.

To all whom it may concern:

Be it known that we, WILLIAM A. BOCK and RICHARD G. BOCK, both citizens of the United States, and residents of Chicago, 5 Cook county, State of Illinois, have invented new and useful Improvements in Rail Anchors, of which the following is a specification, reference being had to the accompanying drawing, in which—

10 Figure 1 is an end elevation of our improved rail anchor showing the same applied to a rail, the latter being illustrated in section. Fig. 2 is a top plan view of a portion of a rail, a portion of a tie and our improved rail anchor applied thereto. Fig. 3 is a top plan view of one member of our rail anchor, the full lines showing the operative position of said member, on the rail, the latter being indicated by dotted lines, 15 and the dotted position of said member indicating the position in which it is first applied to the rail. And Fig. 4 is an end elevation of the rail anchor, showing the opposite end to that illustrated in Fig. 1, the arm 20 or extension of the follower being illustrated in section. The position of the plate shown in elevation corresponds to the dotted position of the same member illustrated in Fig. 3.

25 The object of our invention is to provide a rail anchor of simple and cheap form which may be made entirely by casting and wherein the parts automatically increase the grip on the rail as the latter tends to creep, 30 the gripping being effected by a relative twisting of the rail anchor parts.

Referring to said drawing, A denotes a gripping plate; B a follower or locking bar coöperable with said plate; C a section of a 35 standard rail; and D a tie.

The gripping plate A, as shown, comprises a horizontal portion 10 provided at each end thereof with upwardly extended inwardly flanges 11 and 12 adapted to fit over 40 and firmly grip the edges of the rail base. The gripping flanges 11 and 12 extend diagonally to the axis of the rail when the plate A is arranged at right angles to the rail, as clearly indicated by dotted lines in 45 Fig. 3 and said gripping flanges 11 and 12 are so spaced that the plate A may be fitted over the rail base when at right angles to the rail. After the plate A has been applied to the rail base as above described, it is 50 turned at an angle thereto as indicated by

the full lines in Fig. 3, in which position it will be apparent that the flanges 11 and 12 overlap the edges of the rail base and firmly grip the latter. The plate A is also provided in the top face of the portion 10 thereof with a groove or channel 13 which extends at an acute angle to the axis of the rail when the plate A is in operative position, as shown at full lines in Fig. 3. The gripping flanges 11 and 12 are preferably 55 reinforced by suitable ribs 14—14.

The follower or locking bar B, as shown, is provided with a single rail gripping flange 15 also suitably reinforced by ribs 16; a depending flange 17 which serves as 60 a tie abutment and is located to one side of the center of the rail, when in position, the abutment being nearer that side of the rail on which the flange 15 is seated than the other edge of the rail; and an extension 70 75 or arm 18 of substantially rectangular cross section and adapted to slide within said groove or channel 13 of the gripping plate A. The arm or extension 18 is inclined to the axis of the rail at an acute angle when 80 the follower B is in position, the angle corresponding to the angle of the channel or groove relatively to the axis of the rail. The depending flange or abutment 17 may be 85 suitably braced as by the rib 19.

In applying the rail anchor to a rail, the follower B is put in position against the tie 90 D; then the gripping plate A is applied to the rail as hereinbefore described and most clearly illustrated in Fig. 3, whereupon the member A is moved longitudinally of the rail toward the follower B. The arm 18 of the latter enters the groove 13 and as the gripping plate A is hammered home, it is apparent that the members B and A will be 95 relatively twisted, thus causing a pinching of the rail at three spaced points, two on one edge and one on the opposite edge. Any tendency of the rail to creep will naturally shift the plate A toward the follower B and 100 automatically increase the gripping action between the members. As is apparent from the preceding description, no tapered or wedging surfaces are employed or necessary and the gripping action is entirely independent of such surfaces. Consequently, 105 loosening of the parts resulting from alternating expansion and contraction under the influence of heat is overcome, one of the defects of prior types of rail anchors, which 110

are dependent upon a wedging action to maintain the grip.

As will be apparent to those skilled in the art, various changes and modifications may be made in the details of construction and arrangement of parts without departing from the spirit of the invention and we contemplate all changes and modifications that come within the scope of the claims appended hereto.

We claim:

1. A rail anchor comprising, a gripping plate having portions thereof arranged to grip opposite edges of a rail base, and a locking bar arranged to engage a tie, said bar having means to engage one rail base edge only and an extension coöperable with said gripping plate, the extension being at an angle to the axis of a rail and thereby effecting a twisting action of the plate and bar upon relative approach thereof.

2. A rail anchor of the character described comprising, a gripping plate having flanged ends arranged to grip opposite edges of a rail base, said gripping plate extending at an angle to the axis of the rail when in operative position, and a follower having a tie engaging abutment, said follower being provided with means for gripping one edge of a rail base and having an arm extending at an angle to the axis of the rail, said arm passing through and engaging a channel in said plate.

3. A rail anchor of the character described, comprising, a follower member having means for engaging one edge of a rail and an abutment to engage a tie, said follower member being provided with an arm extending at an acute angle to the axis of the rail when in position, and a gripping plate extending transversely to the axis of the rail, said plate having a channel to receive said arm, the follower and plate being twisted relatively to the rail base to grip the latter as the plate is forced toward the follower.

4. A rail anchor of the character described, comprising, a follower having a flange at one side thereof arranged to engage over and grip one edge of a rail base, said follower having a depending flange arranged to abut a tie, said follower being provided also with an arm extending at an acute angle to the axis of the rail when said follower is in position, and a gripping plate extending normally at an angle to the axis of the rail and having flanged ends arranged to engage and grip the opposite edges of a rail base, said plate having a channel to receive said arm, the channel being inclined to correspond with the angle of said arm relatively to the axis of the rail, whereby, as the plate moves toward the follower, the

two members are relatively twisted and more firmly grip the rail base.

5. A rail anchor of the character described comprising, a follower having an upwardly and inwardly turned flange at one side thereof arranged to grip one edge of a rail base, said follower having a depending abutment adapted to engage a tie and provided also with an integral arm extending at an angle to the axis of the rail with which said follower is adapted to cooperate, and a gripping plate extending transversely of the rail and having integral opposed, upwardly and inwardly turned flanges arranged to engage and grip the opposite edges of the rail base, said plate having a recess on its upper face inclined to correspond with said arm and adapted to receive the latter, whereby, as the plate and follower move relatively toward each other, the same are twisted and more firmly grip the rail base.

6. A rail anchor of the character described comprising, a gripping plate having flanged ends arranged to grip opposite edges of a rail base, said ends being offset lengthwise of the rail when said plate is in position, and a follower having a tie engaging abutment, said follower being provided also with means for gripping an edge of a rail base and having an arm extending at an angle to the axis of the rail, said arm being seated in a correspondingly shaped channel provided in said plate.

7. A rail anchor of the character described comprising, a follower having a tie engaging abutment and means for gripping one edge of a rail base, said follower being provided with an arm extending away from the tie engaging abutment and in a direction away from the side on which said means are located, and a gripping plate having means on the opposite ends thereof adapted to engage and grip the opposite edges of a rail base, said means on said plate being offset lengthwise of the rail when said plate is in position, the means on said plate engaging the same edge of the rail base as the means on the follower being farther away from the tie engaging abutment than the means on the opposite end of said plate, said plate having a channel in its upper face within which is received said arm, whereby, upon movement of said plate relatively toward the follower, the plate and follower are relatively twisted to more firmly grip the rail base.
